UNITED STATES PATENT OFFICE

2,437,042

MATERIAL PROJECTING APPARATUS

Robert A. Prosser, Riverside, and Arthur S. Nichols, Oak Park, Ill., assignors to The Illinois Clay Products Company, Joliet, Ill., a corporation of Illinois

Application May 29, 1944, Serial No. 537,947

3 Claims. (Cl. 91—44)

1

This invention relates to material projecting apparatus, and among other objects aims to provide improved apparatus of this character particularly adapted for projecting light-weight cementitious and similar materials.

The nature of the invention may be readily understood by reference to one illustrative apparatus embodying the invention and shown in the accompanying drawing.

In said drawing:

Fig. 1 is a longitudinal cross-section of the apparatus, the lower portion of the apparatus comprising the feed tube being shown in small scale;

Fig. 2 is a cross-section taken on the plane 2—2 of Fig. 1;

Fig. 3 is a section taken on the plane 3—3 of Fig. 1;

Fig. 4 is a section taken on the plane 4—4 of Fig. 1; and

Fig. 5 is a sectional perspective of the water distributing element.

Light weight insulating materials such as exfoliated vermiculite do not project well in the conventional type of cement gun. Exfoliated vermiculite is a type of mica, granules of which on application of substantial heat expand to many times their original size to produce a very light weight refractory material weighing about six pounds per cubic foot. It can be applied as an insulating cement by mixing it with various binders such as bentonite. Bentonite when mixed with water provides a good wet as well as dry bond. Insulation of this type is extensively employed on furnaces such as open hearth, soaking pits, etc., and it is generally desirable to apply the insulation to the furnace walls after the furnace has been brought to heat in order to avoid cracks which would develop if the cement were applied to the furnace while cold.

The illustrative apparatus is highly efficient in applying insulation of this character to hot as well as cold surfaces. As here shown, the gun or projector 10 has a longitudinal bore 11 leading from a mixing and aspirating chamber 12. The latter has a terminal fitting 13 projecting laterally from the body of the gun, to which is connected a large diameter tube 14, preferably of flexible character leading to the supply bin or receptacle 15 containing the light-weight insulating aggregates 16 in dry form.

Suction sufficient to draw the dry aggregates through the tube 14 into the chamber 12 is developed in this instance by an air nozzle 17 projecting into chamber 12, preferably in alignment

2

with the bore 11. An air hose or other conduit is connected to the apparatus by the fitting 18 which includes a manually operated valve 19 for controlling the air.

5 The suction created by the jet of air traveling through the apparatus draws the light-weight materials into the chamber 12 and gives them sufficient velocity to travel through the bore and issue from the discharge outlet 20 without laterally dispersing at the outlet. In other words, the aggregate travels towards the surface to which it is to be applied in a fairly compact stream but without such high velocity as to cause the particles to bounce away or striking such surface.

10 Adjacent the discharge outlet the aggregates are mixed with a liquid, e. g. water, which is uniformly distributed around and in the stream by a distributor ring 21 containing a plurality of small size orifices 22 leading from an annular distributing passage 23, formed in this instance by a channel on the inside face of the terminal flange 24 and the outer face of the fitting 21. Water is delivered to the distributing passage 23 from a conduit 25 extending longitudinally of the device and connected by means of a valve fitting 26 to a supply hose or other conduit.

15 The inner face 27 of the distributor ring is conical in character to provide an expanding terminal orifice leading from the bore 11 without substantial angular recesses in which material may collect. A cleanout plug 28 facilitates cleaning the water passages.

20 The addition of water by means of inwardly directed streams adjacent the discharge orifice assists in preventing lateral travel of the aggregate and serves to confine it in a fairly compact and low velocity stream. The water ratio in insulating cement of this character is not particularly critical and may be increased or decreased to secure the most efficient operation and the least waste of material without regard to whether there is an excess of water. The excess simply evaporates without damage to the insulating layer.

25 Obviously the invention is not limited to the details of the illustrative apparatus since these may be variously modified. Moreover it is not indispensable that all features of the invention be used conjointly since various features may be used to advantage in different combinations and sub-combinations.

Having described our invention, we claim:

30 1. Apparatus for projecting light weight granular solids and the like comprising in combina-

tion a tubular member having a straight bore with an open discharge end, a suction chamber extending at an angle from the entrance to said bore, said chamber being connected with a conduit leading to a supply of said light weight solids, an air jet at the entrance end of and in alignment with said bore discharging a stream of air down said bore and adapted to create a suction in said chamber sufficient to cause said solids to be forced into said conduit and sent into said chamber to join said air stream and to be carried thereby out the discharge end of said bore, and means at said discharge end and around the stream of solids for adding liquids thereto as they leave said discharge end.

2. Apparatus for projecting light weight granular solids and the like comprising in combination a tubular member having a straight bore with an open discharge end, a suction chamber extending at an angle from the entrance to said bore, said chamber being connected with a conduit leading to a supply of said light weight solids, an air jet at the entrance end of and in alignment with said bore discharging a stream of air down said bore and adapted to create a suction in said chamber sufficient to cause said solids to be forced into said conduit and sent into said chamber to join said air stream and to be carried thereby out the discharge end of said bore, and an annular liquid distributor at the end of and around said bore, said distributor having outwardly converging jets to deliver liquid to the stream of solids issuing from said bore and in the direction of travel of said stream.

3. Apparatus for projecting light weight granular solids and the like comprising in combination a tubular member having a straight bore with an open discharge end, a suction chamber extending at an angle from the entrance to said bore, said chamber being connected with a conduit leading to a supply of said light weight solids, an air jet at the entrance end of and in alignment with said bore discharging a stream of air down said bore and adapted to create a suction in said chamber sufficient to cause said solids to be forced into said conduit and sent into said chamber to join said air stream and to be carried thereby out the discharge end of said bore, and an annular liquid distributor at the end of and around said bore, said distributor having outwardly converging jets to deliver liquid to the stream of solids issuing from said bore and in the direction of travel of said stream.
